METHOD OF FORMATION OF
RADIATOR SHELLSGeorge E. Ireland, Toledo, Ohio, assignor to The
City Machine & Tool Company, Toledo, Ohio,
a corporation of Ohio

Application April 25, 1930, Serial No. 447,379

13 Claims. (Cl. 113—116)

My invention has for its object to provide a method of forming automobile radiator shells of sheet metal from an oblong strip having relatively small dimensions as to length and width, and that may be readily bent to conform to the shape of one-half of the shell. The sheet metal has a width slightly less as double the width of the metal of the finished shell, plus the width of the work holding area for holding the sheet while it is being die-pressed to the required shape. The length of the sheet is slightly less than one-half the length of one side of the shell, plus the portion of the sheet that affords the required gripping area for holding the sheet by the die-holder plate during the stretching of the central portion of the metal. In order to equalize the stretch, or draw, of the metal during the formation of the shell, the two sides of the shell are formed from the oblong sheet by the dies and are, subsequently, severed from each other along the medial line of the plate. The work holding areas, gripped by the die-holding plate and the work plate, are trimmed from the sheet, the metal of the two parts of the shell having been substantially equally drawn throughout all its areas. The two parts are then butt-welded. If desired, the two parts may be butt-welded to a central decorative part.

The invention may be utilized in methods of operation that vary in their details and, to illustrate a practical application of the invention, I have selected a method that makes use of the invention, and shall describe the steps of procedure and a shell that is formed thereby, the structure formed in each of the steps is shown in the drawing.

Fig. 1 illustrates a perspective view of the structure when first removed from the press. Fig. 2 is a view of a section taken on the plane of the line 2—2 indicated in Fig. 1. Fig. 3 illustrates the parts formed when the structure shown in Fig. 1 has been trimmed and the parts of the shell have been separated. Fig. 4 is a view of a section taken on the plane of the line 4—4 indicated in Fig. 3. Fig. 5 illustrates the parts of the shell when the forward edge, with reference to the radiator, has been shaped. Fig. 6 is a view of a section taken on the plane of the line 6—6 indicated in Fig. 5. Fig. 7 illustrates the parts of the shell assembled. Fig. 8 is a top view of the completed shell.

In carrying out the method involving the use of my invention, a sheet of steel having a length substantially that indicated by the edge 1 of the structure illustrated in Fig. 1, and a width substantially as indicated by the edge 2 of the said structure, is readily arched, as indicated at the

point 3 of the edge of the said structure, and bent, as at 4, when it is placed on the work plate of the die-press. This provides for work holding areas 5 and 6, located at the ends of the oblong sheet, and the work holding areas 7 and 8, located along the side edges of the sheet. These areas, particularly in the region of the maximum draw on the metal, is, preferably, further gripped by ridges and recesses, located on the work plate and the work holding plate, to prevent the movement of the metal in the vicinity of the edges of the sheet metal plate into the central areas that are drawn by the dies.

The cross section of the shell is L-shaped and, in order to produce a uniform drawing of the metal, particularly at the maximum depth of the arch that occurs at the bend of the arch, the right- and left-hand sides are formed from the single sheet of metal. Forming the two halves of the shell at the same time enables the formation of the structure, having like opposite side portions, and the production of the same amount of draw in the metal in opposite directions, and thus produces a uniform stretch of the metal. It produces a balanced resisting pressure on the dies.

When the structure has been formed, as indicated in Fig. 1, the holding areas 5, 6, 7, and 8, may be trimmed therefrom and the right- and left-hand sides of the shell formed by cutting the structure along a medial line to produce the parts 15 and 16, illustrated in Fig. 3. The edges 17, of the parts 15 and 16, may then be shaped to form a ledge 18 where the shell makes contact with the face of the radiator core.

If desired, the end edges 19 may be butt-welded to complete the formation of the shell 23. Preferably, however, a member 20, having an opening 21 for the neck of the radiator, is butt-welded between the end edges 19, which completes the formation of the shell.

I claim:

1. The method of forming a radiator shell which consists in bending a sheet metal strip into curvilinear formation to conform substantially to the bend of one-half of the shell securing edge portions of the strip by the work plate and the die-plate holder, and die-pressing the central portion of the plate to simultaneously form the right- and left-hand portions of the shell integrally interconnected on longitudinal margins to draw the metal of the sheet to the same extent in corresponding parts of the opposite sides of the shell, trimming the die-plate holding areas from the plate and separating opposite sides by cutting the sheet plate along a lon-

gitudinal medial line and butt-welding two of the end edges to connect the severed parts together.

2. The method of forming a radiator shell which consists in bending a sheet metal strip into curvilinear formation to conform substantially to the bend of one-half of the shell securing edge portions of the strip by the work plate and the die-plate holder, and die-pressing the central portion of the plate and thereby simultaneously forming the right- and left-hand portions of the shell side by side in integrally united relation by drawing the metal of the sheet to the same extent in corresponding parts of the opposite sides of the shell, trimming the die-plate holding areas from the plate and separating opposite sides by cutting the formed sheet plate along a medial line, and butt-welding two of the end edges for connecting the said parts together in reverse relation.

3. The method of forming a radiator shell which consists in bending a sheet metal strip into the approximate form of half of a radiator shell, forming the bent plate into curvilinear channel formation thereby simultaneously forming the right and left hand portions of the radiator shell by a balanced forming operation, longitudinally splitting the curvilinear channel formation and terminally interconnecting by welding one to the other the longitudinally divided portions in reverse relation.

4. The method of forming a radiator shell which consists in forming a sheet metal strip into a curvilinear channel-shaped body, thereby simultaneously forming opposite side portions of the completed shell by a balanced forming operation, longitudinally dividing the curvilinear channel body along the bottom of the channel and interconnecting by welding the divided portions end to end in reverse relation.

5. The method of forming a radiator shell assembly which consists in forming right and left curvilinear channel shaped body portions from sheet metal thereby forming opposite side portions of the completed shell, separately forming an ornamental intermediate member and interconnecting one end of each body portion to the intermediate member thereby forming an integral radiator shell assembly.

6. The method of forming a radiator shell which includes bending a sheet metal blank into curvilinear form to conform substantially to the bend of one-half of a radiator shell, die pressing the blank to form one side portion of the shell by drawing the sheet metal, trimming the portion thus formed and attaching an end thereof to a medial portion of the radiator shell.

7. The method of forming a radiator shell, having two side portions and a central portion which consists of forming each side portion from sheet material bent into curvilinear formation to conform substantially to the bend of one-half of the shell, securing edge portions of the sheet material by the work plate and die plate holder and die pressing the central portion thereof to form one portion of the shell, separately forming an additional section to be disposed medially of the assembled radiator shell, trimming the die plate holding areas from the material, arranging the formed side portions in reversely disposed ter-

minally aligned relation and fixedly securing the ends of the side portions of the shell in such relation to the medial portion thereof.

8. The method of forming a radiator shell which consists in bending a sheet metal blank into approximate shape of one-half of a radiator shell, contouring the bent sheet metal blank by die pressing the same to form therein the shape of substantially one-half of a radiator shell, trimming the contoured half radiator shell form, and terminally uniting one such contoured form with another like contoured form in reversely disposed relation to afford an integral symmetrical radiator shell.

9. The method of forming a radiator shell from sheet metal which includes the steps of bending a sheet metal blank to approximate shape of one-half of a radiator shell, contouring the bent sheet metal blank by die pressing to form therein the shape of substantially one-half portion of a radiator shell, trimming the contoured radiator shell portion, forming separately therefrom an ornamental section to be disposed intermediate two reversely disposed contoured side portions of the radiator shell and terminally uniting one such contoured radiator shell portion to each side of the intermediate ornamental section.

10. The method of forming a radiator shell which consists in die pressing from sheet metal a pair of complementary channel shaped sections each including integral vertical and transverse portions, trimming the contoured radiator shell sections, and terminally uniting corresponding portions of the die pressed sections one with the other in reversely disposed fixed relation in a common plane to afford a unitary symmetrical radiator shell.

11. The herein described method of producing a composite radiator shell including the steps of forming from sheet metal a pair of complementary curvilinear channel shaped elements each including integral vertical and transverse portions; reversely disposing the sections in relatively fixed relation in a common plane to afford a continuous unitary radiator shell including fixedly mounting a separately formed ornamental panel medially of the transverse top portion of the shell.

12. The herein described method of forming radiator shells including forming two channel shaped curvilinear sections, each including integral vertical and transverse portions, reversely disposing the sections in a common plane, terminally connecting the reversely disposed sections one to the other into a continuous integral radiator shell and fixedly securing a separately formed ornamental section to the shell in symmetrically disposed relation to the respective sections thereof.

13. The herein described method of producing radiator shells including the steps of forming from sheet material a pair of complementary channel shaped curvilinear sections each including integral vertical and transverse portions, arranging the curvilinear sections in reverse relatively fixed relation to form a unitary radiator shell including mounting a separately formed ornamental section at the top of the shell in overlapping relation with the respective sections thereof.
